UNITED STATES PATENT OFFICE.

CLIVE W. LANPHERE, OF NEW YORK, N. Y.

CURVED BOLT LOCK.

Application filed October 18, 1924. Serial No. 744,327.

The present invention relates to improvements upon the lock shown in my copending applications Serial Number 563,645, filed May 25, 1922; Serial Number 617,235, filed 5 February 6, 1923; and Serial Number 671,820, filed October 30, 1923.

The type of lock disclosed in the aforementioned cases is an automatic and manual lock having an arcuate bolt which is adapted 10 to be projected into interlocking engagement with a keeper so that the lock is not capable of being jimmied.

An object of my invention is to provide a lock of the jimmie-proof type which is of 15 simple design and which has its operating parts arranged in compact form.

A further object of my invention is to provide a lock of the arcuate bolt type having relatively few operating parts, but which 20 possesses all of the essential elements of standard locks.

A further object of my invention is to provide a lock of the arcuate bolt type which is rugged in construction and easily operated. 25

A still further object of my invention is to provide a lock of the arcuate bolt type in which the bolt is pivotally mounted in such a manner that it may be projected or retracted with the minimum resistance. 30

A still further object of my invention is to provide a lock having an arcuate bolt and in which the mechanism for operating the bolt is disposed within the path described by the bolt. 35

A still further object of my invention is to provide a lock of the arcuate bolt type embodying a latch, which may be conveniently operated by one hand. 40

Other objects of my invention will appear 45 as the description is read.

The present invention relates to a lock having an arcuate bolt which is automatically or manually projected into interlocking engagement with a keeper. The bolt moves 50 in an arcuate path, first passing through an opening in the face of the lock, then through an opening in the keeper, then in a curved path through the keeper emerging through an opening in another part thereof, then into 55 another opening in the face of the lock. The bolt is locked in this position so that it can not be returned without first disengaging the locking mechanism.

Because of the fact that the bolt twice passes across the gap between the door and the jamb, the door is secured against movement at two points spaced a distance apart, thus the bolt furnishes in effect two locking bolts for preventing swinging movement of the door. At the same time, because the bolt 60 engages the keeper in a curved path, it is impossible to separate the bolt from the keeper by the insertion of a jimmie or other tool between the door and the jamb. It will thus be seen that the lock constructed in 65 accordance with my invention can not be jimmied and that it effectively interlocks the door and the jamb together.

The above type of lock is disclosed by me in the several prior copending applications 70 referred to heretofore. The present invention contemplates improvements upon the locks disclosed in such applications, although fundamentally the principles of operation are essentially the same. The improved features deal primarily with the simplification of the operating mechanism, a rearrangement of the parts so as to obtain a more compact construction, the balancing 75 of the operating parts so as to obtain ease of operation, and the provision of means for permitting operation by one hand. At the same time the rugged construction of the lock has been preserved if not improved 80 upon.

Specifically, the improved features are the positioning of the bolt controlling mechanism within the circular path described by the bolt; the mounting of the bolt upon a wall of the lock casing so that it is free to move in either direction with a minimum amount of resistance; the simplification of the locking tumbler and the releaser mechanism whereby the number of operating parts are reduced and their operation rendered more certain and with less difficulty; the provision of mechanism for an arcuate bolt and a latch which permits single hand operation. Other features which have been incorporated in the present lock will appear from the detailed description. 95

The invention will be more fully understood by referring to the accompanying drawings, in which—

Fig. 1 is a plan view of the lock with the bolt in its retracted position, the cover be-

ing removed, the keeper with its housing and bolt in projected position being shown in dotted outline.

Fig. 2 is a sectional view on line II-II, Fig. 1.

Fig. 3 is a plan view of the face plate of the lock.

Fig. 4 is a detail view showing the position of the tumbler for locking the bolt in its projected position and about to be engaged by the spindle arm to be removed from such position prior to the retraction of the bolt.

Fig. 5 is a view partly in section of the
13 lock in position within a door.

Fig. 6 is a detail view of the interior escutcheon bolt spindle catch.

Fig. 7 is a view taken substantially on line VII—VII in Fig. 1 but with the cover 20 of the casing in place to show a latch locking mechanism.

Fig. 8 is a side view, on a reduced scale, of the keeper or guard.

Fig. 9 is a front view of the keeper.

Fig. 11 is a view of the inner side of the cover plate of the lock casing.

Fig. 12 is an edge view of the plate shown in Fig. 11.

Fig. 12^a is a fragmentary view of a door showing the relative position of the key cylinder with respect to the jamb.

Fig. 13 shows the mechanism for rendering the bolt inoperative when applied to a rim lock.

Fig. 14 is an enlarged section taken on line XIV-XIV in Fig. 13.

Fig. 15 shows a modified form of the operative parts of the lock including a spiral spring.

Fig. 16 is a view taken on line XVI—XVI in Fig. 15, showing a modified locking pawl to receive an end of a spiral spring. Fig. 17 is a modified locking pawl.

Fig. 17 is a modified lock structure embodying my invention and showing means associated with the key cylinder for retracting the latch.

50 Fig. 18 is a fragmentary view of a cover plate for the lock shown in Fig. 17.

Fig. 19 is a view of the under side of the cover plate shown in Fig. 18.

the cover plate shown in Fig. 18.

55 Fig. 21 is a sectional view of the operative parts of a lock as shown in Fig. 17 and illustrates the operative relation between the bolt and the key barrel, and

Fig. 22 is a view taken substantially on line XXII-XXIII in Fig. 17.

line XXII—XXII in Fig. 17.
An embodiment of the present invention
as shown in the preferred form is applied to
a lock of the mortise type, although equally
useful and practical when applied to the
rim type lock.

A lock embodying the invention may include a casing or housing 15 comprised of a bottom wall 16 and side walls 17, 18, 19 and 21. The side wall 17 is extended at each side from the casing to provide a facing 22 and a face plate 23 may be provided and secured to the facing by screws 24. A cover plate 25 may complete the housing and may be fastened in position by suitable machine screws or tap bolts screwed into tapped holes 26. 70 75

My lock mechanism may comprise an arcuate bolt 27 having a tongue 28 integral with an extended rear portion or tail piece 29, a stem 31 and a fin or radius arm 32. The arm 32 may be of fan shape having its broader portion integral with or suitably fastened to the extended tail 29 of the tongue. The opposite smaller end of the fin or arm 32 may terminate in a hub 33 movable in a raceway or annular groove 34 formed in the bottom wall 16 about a bearing aperture 35 in which a stub shaft 36, termed a spindle, may be disposed for rotation. The shaft 36 may be provided with a shoulder 37 for disposition in a counterbore of the aperture 35. The arcuate bolt 27 is rotatable independently about the shaft 36 and may be oscillated by a manipulation of a knob 37' (see Fig. 5) attached to the shaft in a manner to be later described. Means for anti-frictionally retaining the arcuate bolt in its operative position may include a retainer ring 38 secured to the casing by screws 39 in threaded apertures adjacent the perimeter of the aperture 35. The ring or washer 38 is of a proper dimension to overlap the hub 33 and a circumferential ridge 41 may be provided upon the hub to enclose the ring. The end 42 of the stub shaft 36 which projects into the casing is preferably shaped to rectangular form for insertion into a centrally disposed aperture in a bolt actuating member or cam plate 44 having a cam rise 45, and the hub 33 of the bolt may have a lug 46, as shown in Fig. 1, or a recess 45' as shown in Fig. 4, for the purpose to be presently described. The plate 44 may be secured to the shaft 36 by screws 47. A spiral spring 48 has one end positioned in a slot 49 in the end 42 of the stub shaft 36 and the opposite end in a slot 51 provided in an extended portion 52 which also constitutes a contact boss and is carried on the arm 32 of the arcuate bolt 27. The portion 52 serves to engage with a stop lug 50 on the cam disk to limit the movement thereof. The bolt 27 is constantly urged to its projected position by reason of a spring 53 disposed upon the stem 31 between a plate 4 secured to the stem and a ring 55 in contact with a slotted stop 56 secured to the bottom wall of the casing. The stem 31 may be removably attached at one end to a shoulder of the tongue by screws 57 and the op-

posite end of the stem may fit into a recess 31' in the free end of the tail piece 29.

When the bolt is in its retracted position, the spring will be under compression and the bolt is held in position in opposition to the action of the spring by a reciprocable member 58 which serves as a bolt detent and releaser. One end of said member is provided with a lip 59 adapted to engage with a projection 61 extending perpendicular to the surface of the arm 32 of the bolt and secured thereto. The projection is provided with a notch 62 in which the lip may engage should the operator fail to fully retract the bolt when opening the door. The notch 62 therefore assures the retention of the bolt under normal conditions as the door can not be opened until the bolt is retracted far enough for the lip 59 to engage the notch 62. The opposite end of the retainer member 58 terminates in a beveled latch piece 63 positioned in an aperture 64 in the plates 22 and 23. The latch piece is arranged to engage with the surface of a keeper or guard 65 secured to the jamb of a doorway. The keeper is indicated in dotted lines in Fig. 1. When a door with the present lock applied is moved to bring the latch piece 63 into engagement with the keeper, the latch piece and consequently the retainer member 58 will be moved in a direction to remove the lip 59 from engagement with the projection 61 and notch 62 and release the bolt for projection.

The retainer member may be provided with a body portion 66 slidable on suitable tracks 66' (Fig. 5) and may be also provided with an elongated slot 67 (Fig. 1). An abutment 68 is provided to project into the slot when the retainer or releaser member is in its operative position. The abutment may be integral with the casing and serves to engage one end of a spring 69 positioned in the slot between an end 71 thereof and the abutment. The spring 69 may act to normally move the latch outwardly to an operative position with respect to the guard 65. The releaser or retainer member is, therefore, operable to hold the bolt in its retracted position and to be automatically actuated to release the bolt so that the latter may be projected.

By reason of the spring 48, the shaft 36 is automatically urged to a normal position after being partially rotated to move the bolt 27 by engagement of the cam disk 44 therewith.

When the bolt 27 is in its projected position, a locking pawl 72, pivoted on a pin or post 73 integral with the casing, engages the lug or shoulder 46, which may be a recess 45', if desired, properly positioned on the periphery of the hub 33 of the bolt 27. The locking means includes a notch 74 in the locking pawl to receive the lug 46, the

pawl being normally urged toward the lug by a bow torsion spring 75 mounted on an anchor and king post 76 and 77, respectively, secured to the bottom wall of the casting.

When the retainer or releaser member is actuated by the guard 65 and the bolt takes its projected position, the pawl engages with the lug or recess 46 on the hub 33 of the bolt and thus locks the bolt in its projected position.

A release of the bolt is, however, readily effected when the same is to be retracted either by a key or by the rotation of the cam disk 44 through the agency of the knob 37'. The knob is associated with the cam disk 44 (see Fig. 5) by means comprising a threaded shank or spindle 79 having a squared portion 81 to enter a rectangular socket 82 in the stub shaft 36. The knob 37' may have a threaded hub 83 for threaded connection to the shank at different positions along its length, and a set screw 84 may be provided to secure the knob to the shank. An adjustment of the knob in accordance with the variation in the thickness of different doors may thus be attained. The set screw 84 in the shank may be employed for securing this adjustment. The pin 146 and series of apertures 147 assist in attaining this adjustment.

The knob, cam plate and shaft are movable as a unit manually and under the action of the spiral spring 48. When the bolt is projected, the cam plate takes a position as shown in Fig. 4 and the cam rise 45 on the plate is in position to engage with the locking pawl 72 as the knob is manipulated to retract the bolt. The operation being first to move the cam rise to raise the locking pawl and then into engagement with an extension 70 integral with the bolt to carry the same to position within the casing where it is retained by reason of the retainer member 58. When the bolt is retracted the ends 85 and 86 thereof are disposed substantially flush with the surface of the face plate 23, thus giving a smooth and finished appearance to the visible portion of the lock.

It is often found desirable to so construct the lock that an automatic actuation of a latch bar 102 may be had by an additional retractive movement of the bolt either through a key or the knob associated with means to be later described. It may be desirable, however, to effect an operation of the lock by means of the key only to cause the retraction of a latch bar 102, stop means being provided to prevent the latch bar operation when the lock is operated by the knob 37'. The stop means may comprise an extension 50a of the lug 50, as shown in dotted lines in Fig. 1.

When the said extension is provided the movement of the cam plate 44 necessary to

move the bolt 27 and actuate the latch operating lever 129^a is prevented owing to an engagement between the extension and an inclined face 66^a of the member 66.

As above mentioned, in order to actuate the latch automatically it is necessary to move the bolt 27 beyond its normally retracted position. When the bolt is projected the member 66 is in the position indicated in dotted lines (Fig. 1) and the end 63 is in contact with the keeper plate 122. When the knob 37' is turned to actuate the cam plate 44 to retract the bolt, the additional movement of the cam plate is prevented by reason of the extension 50^a making contact with an inclined surface 66^a of the member 66. The additional movement of the bolt is thus prevented and no automatic actuation of the latch bar 102 is effected. The operation of the key plug 129 (as hereinafter set forth) to move the bolt and subsequently actuate the latch bar remains the same.

If desirable, the bolt may be maintained retracted by a slide rod 87 having an end 89 adapted to be moved into a notch 91 formed in the bolt 27. The opposite end of the slide rod is provided with a button 92 disposed in an aperture in the plates 22 and 23 and accessible for the purpose of being thrust inwardly to engage the end 89 in the notch 91 and secure the bolt from movement. The slide rod may be movable upon the inner surface of the bottom of the casing and may be provided with a transverse projection 93 to engage with the inner surface of the cover plate. The projection 93 in conjunction with the guides 94, 95, and 96 hold the slide rod 87 from lateral movement. A leaf spring 97 disposed between the aforementioned guides and the track of the releaser member 58 serves to frictionally retain the rod in its inner or outer positions. A projection 25', properly positioned on the cover, also engages the slide rod and the spring 97 to hold them movably at the bottom of the casing. A similar projection 26' serves to engage a flattened extension 93' on a button 98 to hold the same in its operative position.

A removal of the rod 87 from the notch 91 may be effected by a thrust upon the button 98 which is of similar construction to the button 92, the two buttons being associated by a lever 99 pivoted at 101. A movement of one button causes a reverse movement of the other button in a manner common to push button mechanism of this character.

Any suitable latch mechanism may be employed with the present lock, the one shown comprising a latch bar 102 having a beveled end 103 normally projecting through an aperture 104 in the face plates 22 and 23.

The latch bar is normally moved outwardly from the casing under the action of a helical spring 104' positioned between the beveled end 103 and a washer 104" which

engages guide lugs 105. The latch bar is constructed with an extension 106 having a projection 107 to engage with a nosepiece 108 on a yoke 109. The yoke is formed with an arm 111 adapted to rock upon a fulcrum 112 secured to the wall 21 of the casing and is held under tension by engagement with an end 113 of a spring 114 mounted on a post 115. The opposite end of the spring engages one of the guides 105. The yoke 109 is disposed about a hub 116 having a rectangular aperture 117 to receive a shank to which knobs 118 and 119 may be attached in the usual manner. The hub 116 is provided with a lever arm 121 normally engaged with the nose piece 108 of the yoke 109. Thus when a knob is turned, the nose piece effects a movement of the yoke in opposition to the springs 104' and 114 and the latch may be moved into the casing. It will be understood that this latch construction provides for an actuation of the latch independently of any movement of the knobs, as for example, when a door is closed the latch is free to operate and enter an aperture in the guard or keeper.

The latch mechanism employed has a split latch barrel and a two-part spindle in which the knobs on opposite sides of the door are operable independently of each other. A construction of this character is shown in Figs. 17 and 22 and is hereinafter more fully described. Other types such as a one piece spindle and latch barrel may be used.

The keeper 65 which cooperates to complete the present lock mechanism may be similar to that shown in the above-mentioned copending applications and may comprise a plate 122 provided with apertures 123 and 124 for the passage of the tongue 28 of the bolt 27. These apertures may communicate with a housing 125. It will, however, be noted that the housing of the present keeper encloses both the bolt and the latch. The wall 126 of the housing between the apertures 123 and 124 may provide an obstruction or bar to prevent lateral removal of the bolt from the housing.

As above set forth, the bolt may be operated by a manipulation of the knob 37', however, a key cylinder 127 of any suitable type may be provided, whereby a key 127' may be employed to actuate the bolt.

The key barrel or cylinder 127 shown in the drawing may be provided with the usual rose 128 and key plug 129, the inner end of which latter may be equipped with an arm 130. As shown more clearly in Figs. 11 and 12, the arm 130 is substantially tangent to a circle concentric with the longitudinal axis of the key plug. The key barrel is threadedly connected to the cover plate 25 and so positioned that the key plug is eccentrically disposed with relation to the longitudinal axis of the shaft 36. The arm

130, is however, movable to engage the extension 70 integral with the bolt 27. Thus when the key is actuated to turn the key plug, the arm will engage with the extension to throw the bolt. It will further be noted that arm 130 acts in a manner similar to the cam rise 45 and releases the lock pawl 72 from engagement with the bolt, the arm then operating to actuate the released bolt. As shown in dotted lines in Fig. 11, the key slot 130' is normally positioned at an angle to the vertical. This arrangement of the slot adapts the lock to a convenient actuation by a movement of the wrist which is important in a lock of the present type in which the bolt has a relatively long movement.

Although a door may be opened by a manipulation of the knobs 37' and 119 or the knob 118 and a key, mechanism is provided so that a door may be opened by an actuation of either a key or the knob 37' alone. Such mechanism may include an extension 130^a integral with the end 103 of the latch 102. The extension may include a finger 131^a normally in engagement with a long arm 132^a of a lever 129^a pivoted to the bottom wall of the casing and having a shorter arm 133^a associated with the bolt 27. When the bolt is actuated for retraction by either the key or the knob 37', it may be moved until the exposed end of the bolt 27 projects through indenture 135^a and into the aperture 123 of the keeper 65. This movement of the bolt serves to effect a cooperative movement of a lug 134^a on the tail piece 29 and the lever arm 133^a and a consequent retraction of the latch. It is necessary to only permit a slight movement of the end of the tail piece into the keeper, because a very slight movement of the door when opened will cause the end of the latch to be positioned to engage with the face of the keeper and be held retracted during the opening of the door. For the purpose of permitting a movement of the door and at the same time allowing the end of the bolt to project sufficiently to keep the latch retracted, an inclined indenture 136^a (Fig. 10) is provided at one side of the aperture 123 over which the rear end 86 of the bolt may slide but still be sufficiently projected to hold the latch retracted until as above stated the end of the latch engages with the face of the keeper as the door is opened. Then the indenture serves to push the bolt back into the casing, rendering its ends substantially flush with the face of the casing and allowing the door to be swung clear of the jamb.

It may be found desirable to lock the door by means of the latch bar. For this purpose a slide rod 140^a is provided and movably disposed between the guide pieces 141^a integral with the wall 16. (Fig. 7). The slide

bar may extend through a slot 142^a in the wall 16 and may terminate at one end in a cross piece 143^a connected by a spacer member 144^a movable in a slot 145^a in the escutcheon plate 146^a and secured to a finger piece 147^a. The opposite end 148^a of the slide bar 142^a may by means of the finger piece be moved into and out from a notch 149^a in the lever 121 of the split latch barrel which functions to actuate the latch from the outside when the knob 118 is turned. By virtue of the slide bar 140^a it is possible to lock the door without actuating the bolt 27, or both the bolt and latch may be employed and a double lock thus provided. The inside knob is always free to retract the latch.

An important feature of the present lock is the novel means for locking the key cylinder 127 to the casing. As illustrated in Figs. 11 and 12, the key cylinder is provided with oppositely disposed flat surfaces 131 and 132 and the plate 25, in which is screwed the key cylinder, is provided with bosses 133 and 134. The bosses are tapped to receive set screws 135 which may be moved into engagement with the said surfaces and thus prevent rotation of the cylinder 127 and its removal which permits one to engage the bolt mechanism by means of their fingers.

This construction greatly reduces the possibility of any one turning the cylinder by applying a wrench such as a Stillson, to the end of the cylinder which projects from the outside of the door. Heretofore, the cylinder has been held by reason of a set screw which engaged a notch or slot in the cylinder in line with its center. When force was applied the cylinder could be removed. In the present construction the notches are offset with respect to the center of the cylinder and a direct opposing force is applied making it practically impossible to turn the cylinder.

In addition to the above means for securing the cylinder against rotation, a protuberance 141 is positioned on the escutcheon plate adjacent to the projecting portion of the cylinder (see Fig. 5). This protuberance and the closeness of the key cylinder to the jamb serve to prevent the use of a Stillson wrench to get hold of the key cylinder.

In many instances it is desirable to provide means whereby a person within a room may render a lock inoperative from the outside even though the proper key be employed. For this purpose, I provide a slide latch as shown in Figs. 5 and 6. This latch may comprise a reciprocable finger 140 disposed in a suitable recess within the door adjacent an escutcheon plate 141' which may be provided with a slot 142 to receive a separator piece 143 connected to the finger 140 and a push plate 144 movable upon the outer surface of the escutcheon plate. The

end of the finger 140 engaging a bolt cross pin 146 is beveled at 140' to provide for its automatic retraction when the bolt is projected should it be pushed into locking position when the bolt is retracted. This assures a full projection of the bolt. A spring 145 may be provided to hold the parts in frictional engagement with the plate 141'. By manipulation of the push plate, 10 the finger may be moved in the path of the cross pin 146 disposed in one of several holes 147 extending transversely through the threaded shank or shaft 79 of the knob 37', thus preventing a rotation of the knob 15 and the actuation of the bolt. It will be understood that if the knob is held from turning, the extended portion 52 on the bolt will engage with the stop lug 50 and the bolt will be held from movement. The holes 20 147 may be so arranged in the shank 79 as to permit the proper disposition of the pin 146 with relation to the reciprocable finger 140 in accordance with the variation in the thickness of the door to which the 25 lock is applied.

Although the slide latch is shown in the present illustration as positioned vertically, the preferable arrangement of such a latch is horizontal, the movement being transversely of the door.

In the case of a rim lock, I may also provide means to render the bolt inoperative. As shown in Figs. 13 and 14, such means may comprise a push pin 155 movable in a suitable bearing 156 in a wall of the casing of the lock. The push pin 155 may be so disposed that an end 157 thereof may be projected into the path of movement of the bolt 27 of the lock. Thus when the bolt is projected the end 157 may, as illustrated, be moved from a recess 158 in the wall of the casing and serve as a stop to prevent a retraction of the bolt either by a key or the knob. It will be understood that the push pin may vary in construction and may be disposed to engage with any portion of the bolt as good practice may require. The present push pin is provided with a tension member 159 which serves to frictionally retain the push pin in a given position.

Although the present preferred embodiment of the invention shows a helical spring 53 upon the stem to throw the bolt, added impetus may be given the bolt by the spiral spring 48. When the spiral spring is used for the above purpose, the locking pawl 72 may, as shown in Figs. 15 and 16, be provided with a notch 148 and an end 148' of the spiral spring 48 may be attached to the pivot post 73 of the pawl. The opposite end of the spring 48 may be attached to the shaft 36 in the same manner as shown in Fig. 1. With this construction, the stop lug 50 is normally maintained against the extended portion 52 on the bolt and the potential

energy of the spring 48 serves to throw the bolt when the same is released by the means hereinbefore described.

It will be noted that the releaser and retainer member 58 is so constructed that in the event that the same should be in its forward position when the bolt is being retracted, that the latter will effect the automatic retraction of the releaser. This is accomplished by a cooperation between the beveled or chamfered edge 165 of the member 58 and the rounded end 166 of the projection 70 carried by the radius arm of the bolt. A retractive movement of the bolt results in an engagement between the projection 70 and the edge 165 of the member 58, causing the latter to move inwardly, thus permitting the lip 59 to overlap the projection 61 and the notch 62 and permit the member 58 to take its operative position to lock the bolt in its retracted position.

Another feature of my invention resides in the arrangement of the openings of the guard for the bolt (as shown in Fig. 9) so as to assure the movement of the bolt therethrough without friction. In order to secure this end, the bolt openings 123 and 124 in the guard have different clearances for the bolt on the side adjacent the inside of the door to which the lock may be fastened than the clearance between the guard opening and the opening 104 for the latch. Thus when the latch engages the guard, the bolt has a slight clearance, and as a result of such clearance the bolt may be projected through the guard without any possible friction.

In locks of the arc bolt type it has been found difficult and according to many such constructions impractical to properly position the key cylinder with respect to the offset on the jamb of the door. For example, in some locks the key cylinder is so disposed as to necessitate a recess in the ledge of the jamb, said ledge serving as a door stop.

My lock is, however, constructed with a view to meeting the conditions universal in carpentry and as shown in Fig. 12^a of the drawing the key cylinder 128 is so disposed as to be located a proper distance away from the ledge 128^a of a jamb 129^a, the knob 37' as well as other knobs are in consequence located at a suitable distance from the jamb giving room for the hand grip when the door is opened. An arc bolt lock with a key disposed a desirable distance from the edge of the door is novel and of great utility.

The construction shown provides in addition to means for manual retraction, means for manual projection of the arc bolt should the projection springs become broken or dispensed with, if desired. A modification of the above is shown in Figs. 17 to 21 and may include the usual casing having a cover plate 25. The bolt 27 is mounted to be oscillated on the stub shaft 36 shown in Fig. 2, the

several operative parts associated therewith being the same as shown in Fig. 2 and may include the knob 37'. The bolt being manually operated, the stem and the helical spring are dispensed with.

The latch mechanism may be of any suitable construction, and as shown comprises a latch bar 102 having an end piece 103 projecting from a face plate 172. The latch bar 10 may be similar in construction to the one shown in Fig. 1 and a coil spring 173 mounted thereon may engage with the end 103 and 15 guide lugs 174 to normally urge the end piece outwardly. The latch mechanism may include a barrel consisting of two parts 175 and 176 inserted in a sleeve 180 (see Fig. 22). The barrel members may be provided with angular apertures to receive the shanks 177 and 178 of knobs at opposite sides of 20 the door and opposing ends of the shanks may be attached together by a coupler member in the usual manner. The members 175 and 176 are provided with lever arms 181 and 182 respectively, both of which are disposed with their ends engaged with a rocker piece 183 which embraces the two piece barrel of the latch. The rocker piece has a lip 184 engaged with a cross piece 185 secured to an end of the latch bar 102 and an arm 186 which is engaged by a spring 187, a pivot lug 188 integral with the casing serving as a fulcrum for the rocker piece 183.

Each of the parts 175 and 176, which constitute the barrel of the latch, may be oscillated by a manipulation of the respective knobs to effect an independent actuation of the latch bar 102.

When desirable, means may be employed to render the latch in operative from the outer side of the door. Such means may comprise push buttons 191 and 192 movable in apertures in the face plate of the lock. The button 192 may comprise an extension 193 having an offset end 194 to engage with a notch 195 in the lever arm 181 of the barrel part 175. A movement of the end of the extension 193 into or out from the notch 195 will render it possible or impossible to actuate the latch by a movement of the shank 177. A movement of the extension into the notch may be caused by a direct thrust upon the push button 192 and a reversal may be effected by a thrust upon the button 191, which is associated with the button 192 by a lever 196 pivoted at 197.

The bar 102 is free to be moved inwardly without the agency of the knobs and may be operated by movement of the bolt 27 as the same is retracted. Means to accomplish this may comprise a lever 201 pivoted at 202 and having an end 203 disposed in a notch 204 in the end 103 of the latch bar 102. An opposite end of the lever is disposed in the path of a contact lug 205 integral with a cam plate 206. Thus when

the bolt 27 is in its retracted position the latch bar 102 which is operable inwardly independently of the knobs, will be retracted. The lug 205 is shown in dotted lines since the same may be dispensed with and 70 a cam plate similar to 205 may be mounted on the cover plate to actuate the latch through the agency of the key as will presently be described. A shoe in the form of a friction spring 207 may be provided to engage and retain the bolt in its retracted position. A stop lug 208 being provided to limit the movement of the bolt. When the contact lug 205 has actuated the lever 201 to retract the latch it will, when the door 80 is opened and the knob released, move by reason of the spring 48 to its normal position out of engagement with the lever 201. The latch will, therefore, be free to act to secure the door when the same is closed without the projection of the bolt and the door may be opened at will by a manipulation of the latch knobs or by the knob 37'. For the purpose of actuating the bolt by 85 means of a key, the cam plate 206 is provided with a boss 206' positioned to be engaged by the lever arm 130 of the key barrel 127 (Fig. 2), the resultant action being the same as when the knob 37' is turned. For the purpose of actuating the bolt by 90 means of a key, the cam plate 206 is provided with a boss 206' positioned to be engaged by the lever arm 130 of the key barrel 127 (Fig. 2), the resultant action being the same as when the knob 37' is turned. For the purpose of actuating the bolt by 95 means of a key, the cam plate 206 is provided with a boss 206' positioned to be engaged by the lever arm 130 in the opposite direction to engage boss 206' on the cam plate will project the bolt.

As hereinabove mentioned, I may employ other means to cooperate with the key for actuating the bolt. Such means may comprise a super cover 211 having a threaded aperture 212 to receive a key barrel (Fig. 20) and adapted to be secured to an annular ridge 213 integral with cover plate 25 as shown in Figs. 18 and 21. An arcuate slot 214 is provided in the super cover. A spindle or what may be termed a secondary stub shaft 215 (Fig. 21) is mounted in the cover and disposed centrally with respect to the ridge 213. The shaft 215 may project from the underside of the cover and a secondary cam plate 216 may be rotatable therewith. A tension spring 217 having one end secured to the shaft 215 and the other end secured in a clamp 219 integral with the cover, serves to normally hold the plate 216 in an operative position, but not powerful enough to throw the bolt.

The cam plate 216 is provided with an extension 221 having a pin 222 secured thereto and extending through the arcuate slot 214 to be engaged by lever 223 movable with key plug 224 of a key barrel 225 screwed into the aperture 212 in the super cover 211. A movement of the key plug by means of a key will effect a movement of the cam plate 216 which in turn may actuate the lever 201 by reason of a suitably disposed projection 226 upon the plate: the lever may be provided with a fin 227 ex-

tending in the path of movement of the projection 226, as shown in Fig. 17.

From the above it will be evident that by reason of the secondary cover plate 211,

5 the key will serve to cause an actuation of the bolt to retract the same or project it and to cause a retraction of the latch as well. When the door is opened, the bolt will remain retracted by reason of the shoe

10 207 and a reverse movement of the secondary cam plate will be caused by the spring 217 when the key is removed from the barrel. The cam plate will return to its normal position with the projection 221 en-

15 gaged with the boss 221' on the bolt radius arm which permits projecting the bolt when locking same, the latch bar being then free to again be operated to catch in the keeper of the jamb.

20 Although I have deemed it desirable to describe and illustrate certain modifications of my invention in connection with the major invention, I reserve the right to cover the subject matter relating thereto and which is not specifically claimed in the present application, by future applications.

25 Although a preferred embodiment of my invention has been shown and described herein, it is obvious to those skilled in the art that modifications may be made therein without departing from the spirit and scope of the invention as set forth in the appended claims.

What is claimed is:

30 1. A lock comprising a casing, a pivotal bolt having a hub mounted on a wall of said casing, said hub having a recess, and means engaging said recess to hold the bolt in operative position within said casing.

40 2. A lock comprising a casing, a pivotal bolt having a hub mounted on a wall of said casing, said hub having a recess, and a washer engaging said recess to hold the bolt in operative position within said casing.

45 3. A lock comprising a casing, an arc bolt pivotally mounted within said casing, and a clock spring to project said bolt.

50 4. A lock comprising a casing, an arcuate bolt pivotally mounted directly on a wall of said casing, means removably secured to said casing and engaging said bolt to retain the same in operative position, and means for operating said bolt.

55 5. A lock comprising a casing, an arcuate bolt pivotally mounted on a wall of said casing, a washer or ring removably secured to said casing, and engaging said bolt to retain the same in operative position, and means for operating said bolt.

60 6. A lock comprising a casing having a plurality of walls, an arcuate bolt pivotally mounted on one of said walls, means for retaining said bolt in position on said wall, and a clock spring engaging said bolt and

said casing and adapted when placed under tension by rotation of said bolt in clockwise direction to project said bolt.

65 7. A lock comprising a casing, an arc bolt having a hub pivotally mounted on said casing, means for projecting said bolt, and means mounted on said casing and engaging said hub to retain the bolt in its projected position.

70 8. A lock comprising a casing, an arc bolt movable in a curved path, means to operate said bolt, and a pivotal member to hold said bolt in a given position.

75 9. A lock comprising a casing having a plurality of walls, an arcuate bolt having a hub pivotally disposed in a wall of said casing, means for projecting said bolt, and a pivotal member for engaging the hub of said bolt to retain the same in projected position.

80 10. A lock comprising a casing, an arcuate bolt having a hub, an annular groove in said casing for receiving said hub, means for retaining the bolt hub within said groove, a shoulder or recess in said hub, means for projecting said bolt, and means pivotally mounted in said casing and engaging said shoulder or recess to retain the bolt in its projected position.

85 11. A lock comprising a casing, a bolt movable in a curved path and mounted within said casing, and a plurality of springs for projecting said bolt from said casing.

90 12. A lock comprising a casing, a bolt movable in a curved path and mounted within said casing, and a helical and a spiral spring for projecting said bolt from said casing.

95 13. A lock comprising a casing, a bolt movable in a curved path, means for projecting said bolt, a member for holding said bolt projected, a key cylinder mounted in said casing and having an arm to engage the bolt to retract the same, said arm having a rounded corner to pass said member.

100 14. A lock comprising a casing, an arcuate bolt pivotally mounted in said casing, means for projecting said bolt, a pivotal member for holding said bolt projected, a spindle having an arm to rock said member when said arm is moved either clockwise or counterclockwise, said arm also being adapted to engage said bolt to retract the same.

105 15. A lock comprising a casing, a bolt mounted within said casing and adapted to be projected therefrom, a latch normally projecting from said casing, and a key cylinder screwed into said casing and adapted to operate said bolt, said key cylinder being locked in said casing by a plurality of screws engaging said key cylinder off-center.

16. The combination in a lock having a pivotal bolt and means to actuate said bolt, of a latch, means to project said latch, means to retract said latch, and means comprising a rocking member and resilient means to return the latch retracting means to initial position.

17. A lock comprising a bolt movable in a curved path, a latch, common means to 10 actuate said bolt and latch, means to project said latch, means independent of said common means to retract said latch, and means independent of the latch projecting means to return the latch retracting means 15 to initial position.

18. A lock comprising a casing, a pivotal bolt mounted within said casing and adapted to be projected therefrom, a cylinder lock, a spindle detached from the 20 cylinder lock for retracting the bolt, and a knob having a spindle adjustably connected to said first-mentioned spindle.

19. A lock comprising a casing, a bolt movable in a curved path, a latch, a plurality of means to retract said latch, and means to hold said retractive means inoperative from one side of a door, and cooperating means to retract said bolt and latch.

20. A lock comprising a casing, a bolt 30 movable in a curved path and mounted within said casing and adapted to be projected therefrom, a spindle to actuate said bolt, a detachable spindle to actuate the first spindle, an escutcheon, said detachable 35 spindle being mounted on said escutcheon.

21. A lock comprising a casing, a bolt movable in a curved path, means for affecting the operation of said bolt, an escutcheon, and means carried by said escutcheon for 40 holding the bolt inoperative.

22. A lock comprising a casing, a bolt within said casing, means for effecting the automatic operation of said bolt, an escutcheon, and means carried by said escutcheon for holding the bolt in its projected position.

23. A lock comprising a casing, a pivotal bolt mounted within said casing and adapted to be projected therefrom, a spindle for retracting the bolt, a knob having a spindle 50 detachably connected to said first-mentioned spindle, and an escutcheon to hold said knob spindle in position on a door.

24. A lock comprising a casing, a bolt 55 movable in a curved path, means for automatically projecting said bolt and means disposed wholly within the path described by said bolt for holding the same retracted and for effecting the automatic release of said bolt.

25. A lock comprising a casing, an arcuate bolt pivotally mounted on a wall of said 60 casing, means engaging the bolt adjacent the pivotal point for holding the same in its projected position, means engaging the 65 bolt intermediate the pivotal point and the

bolt proper for holding the bolt in its retracted position, means for automatically releasing the last-mentioned means, said releasing means being disposed within the arc described by said bolt.

26. A lock comprising a casing, an arcuate bolt pivotally supported by said casing, and a combined releaser and bolt retaining means wholly disposed within the path described by said bolt.

27. A lock comprising a casing, a bolt pivotally mounted in said casing, means for automatically engaging said bolt when retracted to hold the same in such position, said means being disposed within the arc 80 described by said bolt, a releaser integral with said means and adapted to engage an external member to disengage said means from said bolt, said releaser also being disposed within the path described by said bolt, 85 and a spring within an opening in said releaser and having one end engaging the releaser and the other end engaging a portion of said casing, said spring normally maintaining the releaser in operative position and to effect the engagement of said 90 first-mentioned means with the bolt to hold the same in its retracted position.

28. A lock comprising a casing, a bolt pivotally mounted within said casing, an 95 arcuate-shaped releaser slidably mounted within said casing, one end of said releaser being adapted to normally project from said casing and the other end being disposed within said casing and adapted to engage 100 said bolt to hold the same in its retracted position, said releaser being positioned within the arc described by said bolt, and means for projecting said bolt.

29. A lock comprising a casing, a bolt 105 pivotally mounted within said casing and having a tongue adapted to be projected from said casing in an arcuate path, means for projecting said bolt, means for holding said bolt in its projected position, means for holding said bolt in its retracted position, means for effecting the release automatically of said last-mentioned means, all of said means being disposed within the arc 110 described by said bolt.

30. A lock comprising a casing, a bolt pivotally mounted within said casing, means for retracting said bolt, means for holding said bolt in its retracted position, means for holding said bolt in its projected position, means for effecting the disengagement of the means for holding the bolt in its retracted position, a key cylinder for retracting the bolt, means for rendering said means for effecting the disengagement of the retracted means ineffective, all of said means being disposed within the path of movement of said bolt.

31. A lock comprising a casing, a bolt 130 pivotally mounted within said casing, means

- coaxially arranged with the pivotal point of said bolt for retracting said bolt, said means being operated by a knob, a key cylinder having a movable plug eccentrically 55 arranged with respect to the pivotal point of said bolt to effect the retraction of said bolt, and means disposed within the path of movement of said bolt for locking the same in its retracted position, in its projected 60 position, and to release the means for holding the bolt in its retracted position.
32. A lock comprising a casing, a radius arm pivotally mounted within said casing, a bolt carried by said arm, means for projecting said bolt, means for retracting said bolt, means for holding the bolt retracted, and a plurality of means on said radius arm for cooperating with the means for holding the bolt retracted. 65
33. A lock comprising a casing, a radius arm pivotally mounted within said casing, a bolt carried by said arm, means for automatically projecting said bolt, means for holding the bolt in retracted position, a releaser for disengaging said last-mentioned means from said bolt to permit the automatic projection thereof, said releaser having an offset to permit the passage of said radius arm. 70
34. A lock comprising a casing, a bolt mounted to move in a curved path, and a key cylinder having a plug to actuate the bolt, said plug having a key slot at an off angle to the perpendicular. 75
35. A lock comprising a casing, a bolt pivotally mounted within said casing, means for holding said bolt retracted, means for automatically releasing said bolt, means for projecting said bolt, means for retracting said bolt, and means for retracting the releaser upon retraction of said bolt. 80
36. A lock of the arcuate bolt type, an arcuate bolt, means for retracting the bolt, means to hold said bolt retracted and means 40 for releasing the bolt, said first-mentioned means cooperating with said releasing means to effect the retraction thereof. 85
37. The combination of a guard having three spaced-apart openings to receive an arcuate bolt and a latch, with a lock having an arcuate bolt to engage two of said openings and a latch to engage one of said openings, the openings for said bolt having different clearances on the side adjacent the 45 inner side of the door to which the lock is attached than the clearance between the guard opening and the latch, whereby the projection of the bolt through the guard openings without friction is assured. 90
38. A lock comprising a casing, a bolt movable in a curved path, means for retracting said bolt, a latch disposed within said casing and outside of the path of movement of said bolt, said bolt cooperating with 50 means to retract the latch during retraction of said bolt by said means, and independent means for retracting said latch. 95
39. A lock comprising a casing, a bolt movable in a curved path, a latch within said casing and disposed outside of the path of movement of said bolt, and means cooperating with said bolt and latch to cause the retraction of said latch upon retraction of said bolt. 100
40. A lock comprising a casing, a bolt movable in a curved path, a latch within said casing and normally projecting therefrom, said latch being disposed outside of the path of movement of said bolt, said bolt cooperating with said latch to retract the same upon retraction of said bolt. 105
41. A lock comprising a casing, a door to which said lock is secured, a knob having a spindle supported by said door, one end of said spindle projecting within said casing and adapted to operate a bolt within said casing and movable in a curved path. 110
42. A lock comprising a casing, a door to which said lock is secured, a bolt within said casing and movable in a curved path, an escutcheon plate secured to the door, a knob having a spindle rotatably mounted on said plate, said spindle having an end extending within said casing to actuate said bolt. 115
43. The combination with a lock having a bolt movable in a curved path and a latch, of a closed guard having openings for the passage of said bolt and said latch, the opening for said latch being outside of the path of movement of said bolt. 120
44. The combination with a lock having an arcuate bolt and a latch, of a closed guard having three spaced-apart openings, said bolt being adapted to engage two of said openings and said latch engaging the remaining opening, the latch opening being outside of the path of movement of said bolt. 125
45. A lock comprising a casing, a guard, a bolt adapted to interlock with said guard, a latch engaging said guard, and a key cylinder lock secured to said casing and projecting therefrom and adapted to actuate both the bolt and the latch. 130
46. A lock comprising a casing, a guard, a bolt adapted to interlock with said guard, a latch disposed outside of the path of movement of said bolt and adapted to engage the guard, and common means adapted to actuate both the bolt and latch. 135
47. A lock comprising a casing, a guard, a bolt interlocking with said guard, a latch engaging said guard, and actuating means cooperating with lever means to operate both the bolt and latch, and said lever means, said lever means being normally detached from the actuating means. 140

48. A lock comprising a casing, an automatic bolt, an automatic latch, and a single knob to operate said bolt and said latch.

49. A lock comprising a casing, a bolt adapted to be automatically projected from said casing, means for causing the automatic projection of said bolt upon the closing of a door carrying said lock, a latch, means for automatically projecting said latch, and a single knob for operating said bolt and latch.

50. A lock comprising a casing, an automatic bolt, an automatic latch, and a key cylinder for operating said bolt and latch.

51. A lock comprising a casing, an arc bolt mounted within said casing, a latch disposed within said casing and outside of the path of movement described by said bolt, and a single operating knob for both said bolt and latch.

52. A lock comprising a casing, a bolt mounted within said casing and movable in a curved path, a latch disposed within said casing and outside of the path of movement described by said bolt, and a single means for operating said bolt and latch.

53. A lock comprising a casing, a bolt pivotally mounted within said casing, a latch disposed within said casing and outside of the path of movement described by said bolt, and a single operating knob for both said bolt and latch.

54. A lock comprising a casing, an arc bolt mounted within said casing, a latch disposed within said casing and outside of the path of movement described by said bolt, and a cylinder lock to operate both said bolt and latch.

55. A lock comprising a casing, a bolt pivotally mounted within said casing, a latch disposed within said casing and outside of the path of movement described by said bolt, and a cylinder lock to operate both said bolt and latch.

56. The combination of a casing, an arcuate bolt within said casing and when retracted having its ends slightly projecting beyond the face of said casing, and a removable cover face plate for said casing having openings therein for receiving the ends of said bolt, said openings having the outer edges beveled with respect to the longitudinal axis of the plate and the inner edges at right angles to the longitudinal axis, whereby insertion of the projecting ends of the bolt through said openings is facilitated.

57. The combination of a casing having two spaced-apart openings in its face, a bolt mounted within said casing and when in retracted position having its ends slightly

projecting beyond said openings, and a removable face plate for said casing having spaced-apart openings of such design as to permit the ready application of the face plate over the projecting ends of said bolt.

58. A lock comprising a casing, a bolt adapted to be projected from said casing, a knob spindle for retracting said bolt, a catch for holding said bolt in its projected position, and a chamfered edge on said catch and cooperating with said knob spindle to automatically return the catch to operative position upon projection of the bolt.

59. A lock comprising a casing, a bolt movable in a curved path and mounted within said casing, and plural means for automatically projecting said bolt.

60. A lock comprising a casing, a bolt movable in a curved path, a latch, a plurality of means to retract said latch, and means on one side of a door directly cooperating with said latch retracting means to hold said retractive means inoperative.

61. A lock comprising a casing, a bolt movable in a curved path, a latch, a plurality of means to retract said latch, and means directly co-operating with said latch retracting means to hold said retractive means inoperative from one side of a door.

62. A lock comprising a casing, a bolt movable in a curved path, a latch, and a simple lever or first class lever to actuate said latch.

63. A lock comprising a casing, a pivotal bolt, an actuating spindle, a latch, and a first class lever means disposed between said spindle and latch to actuate the latter.

64. A lock comprising a casing, a bolt movable in a curved path, a spindle to actuate said bolt and key operated means to actuate said spindle, said key operated means being normally detached from said spindle.

65. A lock comprising a casing, a bolt movable in a curved path, a bolt actuating spindle mounted in one wall only of said casing, and a key cylinder to operate said bolt actuating spindle.

66. A lock comprising a casing, an arcuate bolt supported within said casing, a spindle concentrically mounted with respect to said bolt, and a cylinder lock concentrically mounted with respect to said bolt and having a key plug eccentrically mounted with respect to said bolt and co-acting therewith to retract the same.

In testimony whereof, I have hereunto subscribed my name this 15 day of October, 1924.

CLIVE W. LANPHERE.

DISCLAIMER.

1,584,950.—*Clive W. Lanphere*, New York, N. Y. CURVED BOLT LOCK. Patent dated May 18, 1926. Disclaimer filed October 5, 1927, by the patentee.

Hereby enters this disclaimer to those claims in said specification which are in the following words, to wit:

“7. A lock comprising a casing, an arc bolt having a hub pivotally mounted on said casing, means for projecting said bolt, and means mounted on said casing and engaging said hub to retain the bolt in its projected position.

“8. A lock comprising a casing, an arc bolt movable in a curved path, means to operate said bolt, and a pivotal member to hold said bolt in a given position.”

“26. A lock comprising a casing, an arcuate bolt pivotally supported by said casing, and a combined releaser and bolt retaining means wholly disposed within the path described by said bolt.”

“52. A lock comprising a casing, a bolt mounted within said casing and movable in a curved path, a latch disposed within said casing and outside of the path of movement described by said bolt, and a single means for operating said bolt and latch.”

[*Official Gazette October 25, 1927.*]
